UNITED STATES PATENT OFFICE.

PAUL HOFFMAN, OF LA GRANGE, ILLINOIS, AND JAMES B. STRONG, OF SUFFERN, NEW YORK, ASSIGNORS TO RAMAPO AJAX CORPORATION, OF NEW YORK, N. Y., A CORPORATION OF NEW YORK.

SWITCH-POINT GUARD.

Application filed August 7, 1926. Serial No. 127,730.

Our invention relates to switch point guards adapted to be positioned on the outside of a running rail to protect a switch point from the flanges of wheels entering a switch. The invention more particularly relates to the provision of a switch point guard having means for securely holding it in position relative to the running rail, yet permitting its quick and easy assembly and removal, and so arranged as to brace and strengthen the running rail without having a weakening effect on any portion thereof.

The invention especially relates to a switch point guard which is secured in braced position against the running rail without being bolted thereto, but which holds the guard against the running rail and prevents the latter from crowding away from the switch point.

Various other objects and advantages of the invention will be obvious from the following particular description of forms of a device embodying the invention or from an inspection of the accompanying drawings; and the invention also consists in certain new and novel features of construction and combinations of parts hereinafter set forth and claimed.

In the drawings:

Fig. 1 is a plan view of a portion of a railway switch embodying our invention;

Fig. 2 is a plan view of the guard on an enlarged scale;

Fig. 3 is a side elevation of the guard shown in Fig. 2;

Fig. 4 is a section on the line 4—4 of Fig. 2;

Fig. 5 is a section on the line 5—5 of Fig. 2;

Fig. 6 is a section on the line 6—6 of Fig. 2;

Fig. 7 is a section on the line 7—7 of Fig. 2;

Fig. 8 is a plan view of a portion of a railway switch with a guard applied thereto embodying a modified form of our invention; and

Fig. 9 is a section on the line 9—9 of Fig. 8.

In the following description and in the claims parts will be identified by specific names for convenience, but they are intended to be as generic in their application to similar parts as the art will permit.

Referring to the form of the invention shown in Figs. 1 to 7 inclusive, the switch point guard is positioned on the outside of a running rail 10 opposite the switch point 11 of a movable switch rail 12. The guard 13 is of unitary construction, and may be made of any suitable material such as manganese steel. It is of a length sufficient to span or overlie a plurality of ties 14, three being shown by way of illustration, in Fig. 1.

Tie plates 15 recessed to receive the base 16 of the running rail extend outwardly therefrom a substantial distance along the ties to support the base 17 of the guard 13. Each tie plate may have a thickened end, provided with a shoulder 17'. As shown in Fig. 4 there may be a slight clearance between the base of the rail and shoulder 17', due to variation in width of the rail base. As shown in Figs. 4 and 7, the outer end of each tie plate is provided with a ledge 18 or shoulder preferably formed integral therewith and against which the base of the guard rail abuts. Holes 19 are provided for spiking the tie plates to the ties. The web 20 of the guard rail has lugs 22 projecting therefrom at spaced intervals to fit within the fishing space of the rail 10. The base of the guard rail seats upon the tie plates 15 with the outer edge 23 of the base contacting the shoulder or ledge 18 of each tie plate. The base has a width sufficient to prevent overturning or moving, and is secured to the tie by spikes 24 or other suitable means.

Lugs 30 are formed integral with the guard rail to extend beneath and engage the under-side of the base of the running rail. Each of said lugs may be provided throughout its entire length with a reinforcing enlargement or rib 31.

The head 21 of the guard engages the side of the rail head 10 and its tread 33 is flush with the top of the rail head 10. The head is also provided with a vertical flange 34 projecting above the rail head.

Bracing ribs 35 extend from or near the top of the vertical flange 34 to or near the outer edge 23 of the base. Preferably a tie and tie plate are located beneath each of these bracing ribs to increase the rigidity of the structure. The vertical flange 34 preferably extends parallel with the running rail for substantially half of its length and ter-

minates in outwardly flaring portions 41 at the ends of the guard.

- A modified form of the guard is shown in Figs. 8 and 9. In this construction the extension formed integral with the base of the guard rail does not extend outward sufficiently to contact with the end of the tie plate, but is cut off on a line diagonal to its length, thereby forming a wedge face 43. A 10 wedge block 44 having a wedge face 45 adapted to co-operate with the wedge face on the base extension is mounted in the space between the flange 18 on the tie plate and the end of the extension. Said wedge block 15 has a serrated upper face 46 and has a slot 47 formed therein to receive a bolt 48, on which is mounted a serrated washer 49 provided with means to interlock with the wedge plate. A nut 50 provides means for 20 tightening the locking washer in its adjusted position relative to the wedge block so that the wedge block is firmly held in engagement with the wedge face of the extension. The rail base may have a slight variation in 25 width, but as shown in Fig. 9, the wedge plate holds it tight against the shoulder 17. The adjustability of this construction prevents the lost motion common with the use of non-adjustable rail braces, which do not 30 hold the rail base against the shoulder. This arrangement permits any slack between the guard rail and the running rail to be taken up so that a greater variation is permissible in manufacture, and also permits adjustment 35 to be made from time to time without removing any spikes or making additional bolt holes through the ties.
- The use of bolts in constructions of this type is objectionable because the crowding 40 of the main rail away from the switch point is neither prevented nor minimized. In our improved construction, on the contrary, the guard rail, which is supported independently of the stock rail, takes the impact of the 45 wheel, and the crowding of the stock rail is greatly minimized or completely prevented. The extension forming part of the base of the guard rail extends lengthwise of the tie an exceptional distance and in combination 50 with the bracing ribs which run to the head of the guard rail, and may extend up to the top of the guard rail flange, provide an unusually strong, rigid and effective means for preventing overturning or movement of the 55 guard rail. The spaced lugs on the guard rail, which extend beneath the stock rail, provide the rigidity of a unitary structure, yet they permit horizontal movement of the guard rail and stock rail relative to each 60 other while preventing vertical or swinging movement between the two rails. At the same time the spaced lugs do not interfere with the placing of the ties or the use of tie plates, which may be of standard construction.

While we have shown and described and have pointed out in the annexed claims certain novel features of the invention, it will be understood that various omissions, substitutions and changes in the forms and details of the device illustrated and in its operation may be made by those skilled in the art without departing from the spirit of the invention.

Having thus described our invention, we 75 claim:

1. In combination with a running rail, a switch point guard disposed on the outside of said running rail adjacent a switch point, and means for securing said switch point guard to said running rail, comprising a lug integral with said guard and engaging the under-side of said running rail, said lug being provided throughout its length with a re-enforcing rib.

2. A guard rail structure comprising a movable switch point adjacent thereto, spaced lugs engaging the under-side of the running rail and a rib integral with the guard rail spaced from said lug, said rib extending from the head of the guard rail to a point beyond the plane passing through the curved ends of the guard rail.

3. A guard rail structure comprising a movable switch point adjacent thereto, spaced lugs engaging the under side of the running rail and a rib integral with the guard rail spaced from said lug, a tie plate underlying said running rail and guard rail, said rib extending from the head of said guard approximately to the outer edge of said tie plate.

4. A guard rail structure comprising a movable switch point adjacent thereto, spaced lugs engaging the under side of the running rail and a rib integral with the guard rail spaced from said lug, said guard rail comprising a base provided with a relatively wide extension, said rib extending from the head of the guard rail approximately to the outer edge of said extension.

5. A guard rail structure comprising a movable switch point adjacent thereto, spaced lugs engaging the under-side of the running rail, and a plurality of ribs alternately positioned lengthwise of the guard rail, each of said ribs extending from the head of the guard rail to a point beyond the plane passing through the curved ends of the guard rail.

6. In railroad construction, the combination with a running rail, of a switch point guard, and a tie plate provided with an up-standing shoulder, said guard comprising a base having an extension resting on said tie plate, and means for securing said guard adjacent to the running rail, comprising a wedge plate mounted on said tie plate and arranged between said extension and said shoulder.

7. In railroad construction, the combination with a running rail, of a switch point guard and a tie plate provided with an up-standing shoulder, said guard comprising a 5 base resting on said tie plate and provided with an inclined face, and means for securing said guard adjacent to the running rail comprising a wedge plate mounted on said tie plate and arranged between said inclined face and said shoulder.

8. In railroad construction, the combination with a running rail, of a switch point guard, a tie plate provided with an up-standing shoulder, said guard comprising a 15 base resting on said tie plate and provided with an inclined face, a wedge plate mounted on said tie plate and arranged between said inclined face and said shoulder, and means secured to the tie plate interlocking with the wedge plate to hold same in 20 adjusted position.

9. In railroad construction, the combination with a running rail, of a switch point guard, a tie plate provided with an up-standing shoulder, said guard comprising a 25 base resting on said tie plate and provided with an inclined face, a wedge plate mounted on said tie plate and arranged between said inclined face and said shoulder, and 30 having a roughened upper surface and a washer secured to the tie interlocking with the wedge plate to hold same in adjusted position.

10. In railroad construction, the combination with a running rail, of a switch point guard having a base extension disposed on the outside of said running rail adjacent a switch point, a tie plate underlying said running rail and guard, the outer end of 40 said tie plate being provided with an up-standing shoulder, the outer end of said base extension having a diagonal face, means for securing said switch point guard to the running rail, comprising a wedge plate mounted on said tie plate and arranged between 45 said diagonal face and said shoulder, said plate having a roughened surface adapted to engage the corresponding surface on the wedge plate, and a bolt for holding the 50 wedge plate and washer in adjusted position, said bolt being secured to said tie plate.

11. In railroad construction, the combination with a running rail, of a switch point 55 guard, a tie plate having a thickened portion provided with a shoulder, said running rail having a base adapted for engagement with said shoulder and adjustable means for holding said guard in engagement with said rail 60 and for holding said base in engagement with said shoulder.

12. In combination with a running rail, a 65 guard member therefor, supporting means for said guard member comprising a base member and lugs separated from said base

member and integral with said guard member, said lugs underlying said rail.

13. In combination with a running rail, a guard member therefor, supporting means for said guard member comprising a plurality of base members, said base members being disposed entirely on the outside of said rail, lugs integral with said guard member underlying said rail, said base members and said lugs being alternately disposed longitudinally of said guard member.

14. In combination with a running rail, a supporting tie therefor, a guard member for said rail including a base portion, a tie plate underlying said guard member and 80 said running rail, said tie plate being supported by said tie, and means for attaching said guard member to said rail comprising lugs spaced from said tie and underlying said rail.

15. In combination with a running rail, a guard member therefor having a base portion, said base portion having a supporting flange entirely outside said rail, means for attaching said guard member to said rail comprising lugs integral with said guard member, certain of said lugs being 90 adapted to engage the under side of said rail, and others of said lugs being disposed in the fishing space of said rail.

16. In combination with a running rail, a guard member therefor having a base portion, a flange on the upper portion of said guard member, a transverse rib extending from said flange to substantially the end of 100 said base portion, said base portion being disposed entirely on the outside of said rail, and means for attaching said guard member to said rail comprising a lug adapted to engage the under-side of said rail, said lug 105 and said base member being disposed in different planes longitudinally of said guard member.

17. In combination with a running rail, a guard member therefor having a laterally 110 extending base portion, a narrow rib extending from the upper part of said guard member to substantially the end of said base portion, a tie plate underlying said guard member and said rail, and means for securing said members comprising means extending through both said base portion and said tie plate.

18. In combination with a running rail, a guard member therefor having a laterally 120 extending supporting member, a flange on the upper portion of said guard member, a narrow transverse rib extending from said flange to the end of said supporting member, a tie plate underlying said rail and said guard member and securing means extending through said tie plate and said guard member.

19. In combination with a running rail, a supporting tie therefor, a guard member 130

4

having a laterally extending supporting member, a flange on the upper portion of said guard member, a narrow transverse rib extending from said flange to the end of said supporting member, a tie plate underlying said guard member and said rail, said tie plate resting upon said tie, and means for securing said plate to said tie comprising means extending through said base member

on both sides of said rib, said means also extending through said tie plate.
